UNITED STATES PATENT OFFICE.

SAMUEL O. CARRUTHERS, OF PORTLAND, MAINE.

DESIGN FOR A BOTTLE.

No. 37,787.

Specification for Design.

Patented Jan. 16, 1906.

Application filed December 8, 1905. Serial No. 291,001. Term of patent 14 years.

To all whom it may concern:

Be it known that I, SAMUEL O. CARRUTHERS, a citizen of the United States of America, residing at Portland, in the county of Cumberland and State of Maine, have invented a new, original, and ornamental Design for Bottles, of which the following is a specification, reference being had to the accompanying drawings, forming part thereof.

In the drawings, Figure 1 is a side elevation of the bottle in an upright position.

Fig. 2 is a top plan of the same, and Fig. 3 is a side elevation of the bottle resting upon one of the sides or facets.

I claim—

The ornamental design for a bottle, as shown.

SAMUEL O. CARRUTHERS.
